UNITED STATES PATENT OFFICE

SAMUEL G. THOMSON, OF FLUSHING, NEW YORK, N. Y.

RAILWAY RAIL AND RAIL-JOINT

Application filed May 22, 1930. Serial No. 454,575.

This invention relates to an improvement in the upper sections of the rail and splice bar, primarily in the form of the bearing for the splice bar under the rail head, and particularly, the uppermost portion of the bearing adjacent to the under corner of the rail head.

My improvement consists in giving a substantially horizontal position to the upper and outer portion of the splice bar bearing under the rail head, and in some of the forms the under face of the rail head is carried inwardly in a substantially horizontal direction for the greater portion of the width of the under surface of the rail head. This effects economies in metal distribution.

Some of the designs and principles embodying these improvements are related and supplementary to two of my former applications for patent and are part of the same development. This substantially horizontal position of the outermost portion of the splice bar bearing under the rail head is mentioned and described in connection with Figures 1 and 2 of application No. 445,264, dated April 18th, 1930; and also in connection with Figures 3 and 4 of application No. 450,112, dated May 6th, 1930. In the former mentioned application, this upper and outer portion of the bearing is claimed broadly as concave in form, but the concave bearing may lie also at a steep inclination with the horizontal. In the latter mentioned application, this upper and outer portion of the bearing may be flat or concave and may approach the horizontal or be steeply inclined. In this application, this upper and outer portion of the bearing is claimed broadly as lying in a substantially horizontal position, but it may be flat or concave in its form.

The term "substantially horizontal" wherever found in this specification and in the claims, is intended as descriptive of a face which may vary several degrees from the horizontal and still be within the spirit of my invention. The aforesaid term is meant to describe a face that is considerably nearer to an exact horizontal position than to the least inclination that ever has been used heretofore as a fishing angle bearing. There

is a basic mechanical reason that has heretofore prevented the use of less inclination than about 11 degrees for this fishing angle bearing under the rail head. The range has been from 11 to 18 and even 20 degrees, 23 degrees being used in one of the very early designs of T-rail. The former art has shown from the beginning of the development of the T-rail having a splice bar bearing under the rail head, that 11 degrees seems to be the irreducible minimum for the maintaining of the necessary wedging fit in the coacting bearings, and for providing the required amount of metal to take up wear during the life of the rail. An inclination of one-to-four—about 14 degrees—has been and continues to be the usual practice.

My improvements in this application and in the applications mentioned above make it possible for the outer portion of the upper bearing to lie at a very slight inclination. This is accomplished by the use of a novel combination of curved and slanting faces comprising the inner portion of the upper bearing. This affords the necessary abutment against the clamping action of the bolts, and provides metal for wear and the maintenance of tight rail-joints. This novel upper bearing comprising the combination of an enlarged inner portion of its width having a variable steep inclination and an outer portion with a very slight inclination is supplemented in some of the designs by a new type of bearing of the bar on top of the rail foot, a feature developed in my application No. 450,112. Some of these designs are particularly effective when used with an upper bearing having its outer portion lying in a substantially horizontal position. An exactly horizontal position for the outer portion of the bearing would in some cases be most effective; but it is obvious that an under face of the rail head would be impracticable to roll in an exactly horizontal position, and that at least a very slight inclination of this under face is required in order to provide roll clearance, even when the face is only a fractional part of the width of the under surface of the rail head immediately adjacent to the outer under corner. The term "substantially

horizontal" therefore, wherever it is used in this specification and claims with reference to the outer portion of this upper bearing, is intended as describing an under face of the 5 rail head lying at a considerably less inclination with the horizontal than the minimum 11 degrees heretofore used in the art, and preferably nearer in its inclination to an exact horizontal position than to said minimum 11 10 degrees.

The object of my improvement as already indicated and described in the above mentioned applications, is to afford a positive abutment for the top of the bar such as will hold 15 it under the rail head, and also will effectively transmit the vertical rail load to the splice bar, as well as maintain a pinching tight fit at this upper and outer portion of the splice bar bearing.

20 The precise nature of my invention may best be understood by referring to the accompanying drawings, in which I have illustrated a number of the most desirable forms and combinations which my improvement 25 may take. It is presumed, however, that the invention is susceptible of various other modifications without departing from its spirit and scope as defined in appended claims. The manner in which this improvement 30 is used to great advantage in combination with the broad features claimed in the aforesaid applications will also be understood from the description and drawings of said applications.

35 Figures 1 to 4 inclusive are sectional elevations of a rail and a splice bar fitting said rail and illustrating some of the preferable forms, while Figures 5 to 10 inclusive are sectional views of the upper bearing zone of 40 the splice bar head and rail head.

Similar reference characters denote corresponding parts throughout the various figures of the drawings.

The letter H, wherever seen, designates the 45 rail head; W, the rail web; F, the rail foot; B, the splice bar; C, the substantially horizontal portion of the under surface of the rail head; D, the lower bearing of the splice bar on the top surface of the rail foot; line 50 h—h, a horizontal line through the outer edge of face C; line f—f, the centre line of the clamping bolts.

Figure 1 shows a flat face C joined to an enlarged concave under face 1, thus effecting 55 a thickened web which tapers gradually upward almost to the full width of the rail head. This affords a large bearing area for the head of the splice bar against the rail, the lower portion 2 of the bearing abutting 60 the upright face of the rail web. Lower bearing D shows the usual contact of the splice bar against the top face of the rail foot. This wide lower bearing D effects an upward and inward thrust to the bar directly into the 65 enlarged concave upper bearing as the bar is

drawn tight by the clamping bolts. It will be noted that the upward tendency of the bar due to the wedging action at the lower bearing D causes an excess of pressure at C, which pressure gradually diminishes downwardly around the curve. On the other hand, the pressure due to the direct pull of the bolts along line f—f is a minimum at C and increases gradually to a maximum at 2. Thus, a well balanced pressure condition exists 70 thruout the area of the bearing, with the result that a good fit is maintained and a pinching action exerted at C to keep the fit tight at this point.

The pinching action at the under corner 80 of the rail head is due to the substantially horizontal position of the face C, which is the basic idea of my invention. A maximum pressure is maintained by this feature under new and worn service conditions at a point 85 where looseness or a clearance is the usual result in construction designed to swing in at the bottom around a fulcrum as shown at 2 in Fig. 1 as wear takes place. As the bar is wedged upwardly by being pulled inwardly 90 at D by the clamping bolts, the tendency of the head of the bar to slip upwardly and outwardly in its upper bearing is resisted by the substantially horizontal position of the uppermost portion of the bearing. This lateral position of this uppermost face becomes 95 the tightest point and forms an effective barrier against the head of the bar slipping upwardly in the bearing and outwardly away from the rail head. As this outermost portion of the under surface of the rail head approaches a horizontal position it becomes 100 more effective in encircling the inner portion of the head of the bar and thus acting to prevent the rotation of the bar around its 105 own centre,—inward at the bottom and outward at the top,—under the vibration and wear of service. This laterally extending outer portion of the upper bearing also partly 110 neutralizes the tendency of the top of the bar to be forced outwardly under load by the wedging action of the steeply inclined lower portions of the upper bearing. For a given balanced condition of the head of the bar against the rail, the approach of the outer upper portion of the bearing toward a horizontal position allows a corresponding approach of the lower inner portion of the bearing toward a vertical position.

Figure 2 shows an extreme design of rail 115 head with wide lateral under face C, which effects a maximum barrier against outward slipping of the head of the bar and affords a maximum abutment against the vertical rail loads. An important feature of my invention is here illustrated in effecting a more economical distribution of metal than in the usual design of rail shown by dotted line 3. The metal shown between the dotted line 3 and face C may be placed on the top or side 120 125 130

of the rail head where it can be used to increase the stiffness and the wearing life of the rail. The use of this wide lateral under face gives to the upper section of the rail 5 somewhat of the I-beam characteristics in distribution for stiffness. In this design, this wide lateral under bearing face is combined with a maximum upright bearing face 4 against the rail web. As the bar is wedged 10 upwardly by the pull of the bolts against the lower bearing D, the head of the bar is guided directly into the angle by these two faces C and 4 lying almost at right angles to each other. This gives a very effective anchorage 15 for the head of the bar as well as a maximum bearing area, which is particularly desirable for electrically insulated rail-joints. With an angular piece of insulation between the head of the bar and the rail, a lateral face 20 of the width usually provided is afforded to resist the vertical wheel loads, and an additional upright face of equivalent area is effective in preventing the cutting of the insulation by the tightening and wedging 25 action of the clamping bolts.

Figure 3 shows an upper bearing face of parabolic curvature, in which the upper portion approaches a horizontal position. The concavity of the entire upper bearing is less 30 than that shown in Fig. 1, and its upper portion C is very slightly curved instead of the flat tangent face C shown in Fig. 1. A clearance 5 is provided between the head of the bar and the rail web, which, with the lower bearing D of limited width and with an elastic base member 6 under the rail, allows a slight inward swing of the bottom of the bar around the top bearing as a fulcrum under the vibration and wear of service 35 conditions, as the head of the bar slips slightly upward in its bearing against the steeply sloped faces of the upper portion of the rail web. This action results in a tightening of the coating faces at C due to their approach 40 toward a horizontal position. This pinching action at the top when combined with the outer location of the lower bearing D on the rail foot is effective in holding the bar solidly 45 under the rail head.

Figure 4 shows the under surface of the rail head as broken into two flat faces C and 7. The lower bearing D is located at the juncture of the rail foot and web, and lies at an 50 inclination opposite and equivalent to the upper bearing 7, by which combination of faces the bar may be constructed to be reversible. The movement or tendency of the bar under the clamping action of the bolts is directly inward along the centre-line of the 55 bolts f—f. Only slight pressure thus would be exerted against face C, and only to the extent that it deviated from an exact horizontal position. This face C may be changed to act as a strongly supporting under face for resisting the vertical load by decreasing the in-

clination of the lower bearing. This may be better understood by considering that bearing D is cut away from the rail so that the usual lower fishing angle bearing on the upper surface of the rail foot is similar to that shown 70 in Figure 2. With the wedging and clamping action of the bolts acting against this usual inclination, the tendency of the bar would be strongly upward so as to throw an excess of 75 pressure against bearing C.

Figure 5 shows an enlarged sectional view of the zone adjacent to the under surface of the rail head. A uniformly curved face comprises the entire under surface, starting above in a substantially horizontal position C and extending gradually downward and inward to its point of tangency 10 with the vertical face of the rail web. In forming the head of the bar, the same curvature is continued on down to 11, thus affording a clearance between 80 the bar and the rail web. This design gives a cylindrical socket fit with the bearing extending for almost one-quarter of the circumference, and with the radial centre intersected by a vertical plane at the outer face of 85 the rail head. With the lower part of the bar swinging inwardly to take up wear, the upper bearing will slip around slightly in the socket and maintain a good fit at all points, with a maximum upward pressure exerted at the 90 pinch-point C due to its lateral overhang.

Figure 6 shows a concave under surface of the rail head similar to that of Fig. 5, except that in this Fig. 6 the curvature increases as it approaches the horizontal position at C. The bearing of the bar is carried down only part of the way around the curve to 12, thus making of this design more of a lateral under-bearing than a combination of lateral and upright faces as shown 105 in the former figures. The side face of the rail head is cut under slightly, thus somewhat reducing the width of the substantially horizontal overhanging bearing.

Figure 7 shows a very wide and laterally projecting rail head with a flat face C extending sharply inward to its point of tangency with a uniformly curved face of large radius extending downwardly and inwardly to the rail web. The clearance between 110 the head of the bar and the rail extends above the mid-point 13 of the concave under surface of the rail head, thus making of this design even more of a lateral under-bearing type than that shown in Fig. 6. The bearing of the bar against the rail head is only around that portion of its under surface which is adjacent to the substantially horizontal face C.

Figure 8 shows an under and an upright bearing of the head of the bar against the rail similar to that shown in Fig. 2, except that the fillet 14 has a larger radius than the design shown in Fig. 2. This reduces the 120 width of the flat portions of the bearing.

Figure 9 shows a very shallow concave bearing of uniform curvature under the rail head, extending from the inner fillet at 15 through to the under corner to form the substantially horizontal portion C. In this design there is a distinct offset at the juncture of the head and the web of the rail instead of the gradual change in the section of the rail as shown in most of the other figures. 10 In some respects the under-bearing is disposed similarly to the usual flat fishing angle with the usual inclination, the head of the bar also standing free of the rail web. However, the action of the bar in being 15 clamped inwardly against a concave face is much different from the action of the head of a bar against the usual flat fishing bearing. With the concave face, under the clamping action of the bolts, the substantially horizontal pinching-face C holds the head of the bar firmly in place and an excess of pressure is effected at the inner portion of the bearing 15. The vertical rail load exerts an excess of pressure at C, thus giving a good 20 average distribution of the forces over the entire area of the bearing under loaded service conditions.

Figure 10 shows a substantially horizontal bearing C at the inner portion of the under surface of the rail head, and a fillet bearing 30 having a small radius 16. The portion 17 of the under surface outside of the bearing is shown with about the usual fishing angle inclination. A clearance 18 is provided between the head of the bar and the rail web. This design is essentially an inner small-fillet 35 concentrated bearing with an upper lateral face to hold the head of the bar to its position.

40 From the above description, therefore, it will be noted that my improvement in the form of the under surface of the rail head affords a positive abutment for the top of the bar, such as will prevent it from being forced outward from its normal position when wedged upward by the force of the bolts pulling the bar inward along the inclined lower bearing, particularly in the designs where there is, under load, an outward 45 signs where there is, under load, an outward wedging action of the head of the bar against the steeply inclined faces of the rail web and head. The overhanging laterally extending portion of the upper bearing is also particularly effective in transmitting the vertical 50 rail load to the splice bar, and in maintaining a pinching tight fit at this upper and outer portion of the bearing where, in the former art, there often is a tendency to looseness. It will be noted also, that an economic 55 distribution of metal is effected by extending the substantially horizontal portion of the upper bearing sharply inward so as to comprise the greater portion of the under 60 surface of the rail head.

I claim:

1. A T-rail having a portion of the under surface of its head lying in a substantially horizontal position, and a splice bar contacting with said head and with the top of the rail foot outside of the outer edge of said head contact. 70

2. A T-rail having a portion of the under surface of its head lying in a substantially horizontal position, and a splice bar having the outer edge of its bearing on top of the rail foot lying outside of the outer edge of its bearing under the rail head. 75

3. A T-rail having a portion of the under surface of its head lying in a substantially horizontal position adjacent to an under corner of its head, and a splice bar contacting with the top of the rail foot at a greater distance from the rail web than said bar contacts with the rail head. 80

4. A T-rail having a portion of the under surface of its head lying in a substantially horizontal position adjacent to a vertical plane at the side of the rail head, and a splice bar contacting with the top of the rail foot outside of said vertical plane. 85

5. A T-rail having a substantially horizontal face lying adjacent to an outer under corner of its head, and a splice bar contacting with said head and with the top of the rail foot outside of the outer edge of said head contact. 90

6. A T-rail having a portion of the under surface of its head lying in a substantially horizontal position, and a splice bar having its upper portion extending outwardly beyond said under surface and its lower portion bearing on the rail foot outwardly beyond the outer edge of said under surface. 100

7. A T-rail having a portion of the under surface of its head lying in a substantially horizontal position, and a splice bar contacting with said head and having a slanting bearing on the rail foot outside of the outer edge of said head contact. 105

8. A T-rail having a substantially horizontal face forming that part of the under surface of its head which lies adjacent to the under corner of its head, and a splice bar having an upper portion underlying said corner and a lower portion engaging a slanting face on the rail foot. 115

9. A T-rail having a portion of the under surface of its head lying in a substantially horizontal position, and a splice bar having an upper portion adjacent to the rail head extending outwardly beyond its contact with said under surface and a lower portion having a slanting engagement with the rail foot. 120

10. A T-rail having a portion of the under surface of its head lying in a substantially horizontal position, and a splice bar having an enlarged head and a reduced upright web extending outwardly beyond the outer edge of its contact with the rail head. 125

11. A T-rail having a portion of the under surface of its head lying in a substantially horizontal position, and a splice bar having a portion of its bearing under the rail head 5 lying at a greater angle to the horizontal than any portion of the lower bearing of the bar against the rail, said lower bearing extending outwardly beyond said head bearing.
12. A T-rail having a substantially horizontal face lying adjacent to an outer under corner of its head, and a splice bar having its head projecting outwardly beyond said corner, a portion of the bearing of said splice bar under the rail head lying at a greater 15 angle to the horizontal than any portion of the lower bearing of the bar against the rail.
13. A T-rail having a portion of the under surface of its head lying in a substantially horizontal position and adjoining the fillet at 20 the juncture of the rail web and head, and a splice bar having its upper portion extending outwardly beyond said under surface, said bar contacting with the top of the rail 25 foot and standing free a greater distance from the lower web fillet than the upper portion of the bar stands free from said upper fillet.
14. A T-rail having a substantially horizontal face lying adjacent to an outer under corner of its head, and a splice bar having its head projecting outwardly beyond said corner and inwardly to afford a bearing extending inwardly and downwardly toward 30 the rail web, said bar having the inner edge of a bearing on the rail foot lying at a greater distance from the rail web than the distance of the inner edge of said head bearing from the rail web.
15. A T-rail having a portion of the under surface of its head lying in a substantially horizontal position, and a splice bar having a head bearing at the inner web fillet of the rail and its lower portion bearing on the rail 35 foot, the inner and outer edges of said lower bearing lying a greater distance from the rail web than the inner and outer edges respectively of said upper bearing.

In testimony whereof, I have signed at 40 Flushing, in the city of New York and the State of New York, this 21st day of May, 1930.

SAMUEL G. THOMSON.
